IGNITION APPARATUS

James L. Arthur, Anderson, Ind., assignor to General Motors Corporation, Detroit, Mich., a corporation of Delaware

Application March 14, 1936, Serial No. 68,818

3 Claims. (Cl. 137—139)

This invention relates to ignition apparatus for internal combustion engines and more particularly to the types of apparatus disclosed in my Patent No. 1,761,513, issued June 3, 1930. That patent discloses an automatic ignition controller which adjusts the timing of the ignition in accordance with suction produced by the engine. As the suction increases the spark is advanced and is retarded as the suction decreases. In order to take care of engine idling conditions when the throttle valve is practically closed and the suction in the manifold is high, an automatic valve is used to cut off communication between the engine intake and the suction controller during idling so that the spark will not be advanced during idling. This valve is controlled electromagnetically in response to the voltage of a generator which is driven by the internal combustion engine. When a predetermined voltage is attained corresponding to a predetermined engine speed this valve is automatically opened in order to place the suction controller in communication with the engine intake so that the spark timing will be immediately advanced.

The present invention relates more particularly to improvements in the automatic valve of my Patent No. 1,761,513. The chief object of the present invention is to provide an electromagnetically operated valve for use in an engine suction controlled ignition system with means for so adjusting the electromagnetic device which operates the valve that the valve will place the suction controller in communication with the engine intake at different voltages of the generator driven by the engine, and hence at different engine speeds. The chief advantage of this construction is to permit the use of the same valve with a number of different types of engines. By the use of the present invention the valve can be adjusted so as to take care of varying engine conditions. Some engines require higher idling speed than others. Engines which operate with a relatively low engine idling speed require that the valve open at a relatively low speed and hence at relatively low generator voltage. For use with such engines the electromagnet device would be adjusted so as to place the engine intake in communication with the suction controller at relatively low generator voltage. On the other hand engines which would operate better at higher idling speed would require that the electromagnetic device be adjusted so that the valve opens at a higher generator voltage and engine speed.

Further objects and advantages of the present invention will be apparent from the following description, reference being had to the accompanying drawing wherein a preferred embodiment of the present invention is clearly shown. 5

In the drawing:

Fig. 1 is a diagrammatic representation of an ignition circuit into which the present invention, may be connected.

Fig. 2 is a fragmentary sectional view of the 10 suction control valve and showing the valve in its open position.

Fig. 3 is an end view of the valve looking in the direction of arrow 3 of Fig. 2.

Referring to the drawing, 20 designates a manifold of an internal combustion engine. By suitable gearing, not shown, the engine drives a shaft 21 which in turn drives a rotor 22 of a distributor 23 and a cam 24 of an ignition timer 25. A generator 30 is also driven by the engine in the known manner. The generator 30 is shown diagrammatically and comprises a field winding 31 having one end connected to a main brush 32 and the other end to third or regulating brush 33. The other main brush 34 of the 25 generator is connected by a wire 35 which is connected to a cut-out relay 36. The cut-out relay 36 is of the standard type and is adapted to permit current to flow therethrough in one direction only and in this instance the cut-out relay permits the current to flow from the generator brush 34, wire 35 through the cut-out relay 36, wire 37 into a storage battery 38 to ground 39. The brush 32 of the generator is grounded as at 40. 30 35

The timer 25 comprises a movable arm 41 pivotally supported on a pivot 42 and having a rubbing block 43 engageable with the cam 24. A spring 44 urges the arm 41 toward the cam 24. A contact 45 is carried by the arm 41 and 40 is adapted to engage a stationary contact 46 which is grounded, as at 47.

The ignition coil 50 includes a primary winding 51 and a secondary winding 52. One end of the primary winding 51 is connected to the 45 spring 44 of the circuit interrupter arm 41 through wire 53. The other end of the winding 51 is connected through a switch 54 to the battery 38, and during engine operation to the generator 30. The secondary winding 52 has one 50 end connected to the primary winding 51 and the other end is connected through a wire 55 to a high tension terminal 56 of the distributor 23. The terminal 56 is connected in proper sequence 55

by the rotor 22 to the various terminals leading to the spark plugs of the engine.

The circuit interrupter or timer 25 may be rotated to vary the angular relation of the rubbing block carried by the arm 41 relative to the cam 24 whereby the sparking impulses are retarded or advanced. The cam is rotated in the present instance in the direction of the arrow. If the ignition timer is rotated in a counterclockwise rotation, as viewed from the drawing, the time of the spark impulses will be retarded. When the timer is rotated in a clockwise rotation or in the direction of the arrow the spark impulses will be advanced. The timer housing 25 is provided with an arm 60 to which is attached one end of a rod or bar 61. The other end of the rod 61 is attached to central portion of a flexible diaphragm 62 of a suction actuated device 65.

The device 65 comprises housing members 66 and 67 between which the peripheral edge of the diaphragm 62 is clamped. As shown, the housing member 67 is provided with a flange which is bent over the peripheral edge of the housing member 66. The housing member 67 carries a threaded bushing 68 to which it attached a cap 69 providing a seat for a disc 70 having a small aperture 71. The disc 70 provides a seat for one end of a spring 72, the other end of the spring is received by a cup washer 73 carried by the diaphragm. The spring operates to urge the diaphragm to the left, as viewed in the drawing, to normally hold the ignition timer in a retarded position. The cap 69 receives one end of a conduit 74, the other end of the conduit 74 is connected with a valve body 75. A conduit 74a has one end thereof connected with the body 75 while the other end of the conduit 74a is connected to the engine intake manifold 20.

The valve body 75 is supported on a base 76. This is accomplished by rivets 77 passing through apertured ears 78, which may be formed integral with the body, and pinned over against the underside of the base 76 as shown at 79 in Fig. 3. The body 75 is provided with a through passage 80. The passage 80 is counterbored as at 81 to form a shoulder. This shoulder is countersunk to form an upper seat 82 for a ball valve 83. The passage 80 is further reduced, as at 84, to form a guide for a pin 85. The end of the passage 80 having the larger dimension is threaded to receive a tubular plug 86 having a reduced portion 86a. The end of the reduced portion 86a is countersunk at 82a to form a lower seat for the valve 83. This plug is counterbored, as at 87, to form a shoulder against which is placed an apertured disc 88. The disc is held in place by spinning over a portion of the plug as at 89. Enclosed within the plug 86 is a coil spring 90 having one end bearing against the disc 88, the other end of the spring bears against a headed pin 91. A shank 92 of the pin extends through a restricted portion 93 provided by the tubular plug 86. The spring normally urges the ball 83 against the seat 81. As plug 86 is screw-threaded into the bore 80 the spring 90 will cause the pin 91 to urge the ball valve against the upper valve seat 81.

The body 75 is also provided with transverse passages 94 and 95. The passage 94 is suitably connected with the conduit 74a while the passage 95 is suitably connected with the conduit 74. When the ball valve 83 is yieldably held against the seat 81 by the spring 90, as shown in Fig. 1, the ball 83 shuts off communication between the passages 94 and 95. When the ball valve is in this position or the normally closed position pas-

sage 94 is connected directly with the intake manifold, while passage 95 is connected with the suction chamber 96 of the device 65.

The opening 83a in the washer or disc 88 provides a bleeder which permits pressures within the suction actuating device 65 to return to atmospheric pressure when the ball valve 83 is urged against the seat 82 by the spring 90 to close the passage 94.

The present invention provides electromagnetic means 98 for actuating the ball valve 83 so as to connect the partial vacuum created in the intake manifold with the suction actuated device 65 in order to advance the sparking impulses. The electromagnetic means is suitably supported on the base 76 and includes a core 100 that is magnetically associated with an armature 101. The armature is suitably supported as at 102 and is normally biased away from the core by a leaf spring 103 riveted to the armature as at 104. The leaf spring rests upon an adjustable abutment member 105 integral with the member 106 held in position by the head of the core 100. The abutment member 105 cooperates with the spring to normally hold the armature in a raised position. The abutment member 105 may be adjusted so as to increase or decrease the tension of the spring 103. By bending the abutment member 105 to the right, as viewed in Figs. 1 and 2, the tension of the spring is increased, and by bending the abutment member 105 to the left the tension of the spring 103 is decreased. Increasing the tension in spring 103 increases the amount of magnetic flux of the magnet required to pull the armature 101 down to open the valve and decreasing the tension in spring 103 has the opposite effect. Since magnetic flux is dependent upon current flowing in the magnet coil, and since current depends on voltage of the generator, and voltage on speed of the generator, it is apparent by adjusting the spring 103 one may set the valve so as to cut in the suction control of ignition timing when the generator, and hence the engine which drives it, has attained a certain speed. The member 106 is also provided with an adjustable stop 107 having an offset portion 108 to receive an extension 109 of the armature, as best seen in Fig. 3. The offset portion 108 limits the upward movement of the armature with respect to the core 100 due to the tension of the spring 103. The member 106 can be bent to change the air gap between the core 100 and the armature 101. To increase the air gap between the core and the armature the stop 107 is bent to the right. To decrease the air gap, the member 106 is bent to the left.

Increasing the air gap increases the amount of magnetic flux of the magnet to start the armature 101 in its downward movement to open the valve, and decreasing the air gap has the opposite effect. Hence bending the stop 107 provides an adjustment for the device in order to cause the valve to cut in the suction controller for the ignition timer at a higher or lower engine speed as desired.

The operation of the present invention is as follows: When the engine is not operating, the circuit interrupter or ignition timer 25 will be maintained in full spark retarding position by the spring 72 enclosed within the suction actuated device 65. When the engine starts it will drive the generator 30 to provide current to charge the battery 38. The valve 83 will maintain the passage 94 closed and prevent suction from being exerted upon the diaphragm 62 of the suction

actuation device 65 until the voltage of the generator 30 has attained a predetermined value to operate the electromagnet 99, at which time current will flow through the wire 35 and through the wire 110, which is properly connected with the electromagnet 99, and caused the electromagnet to become energized to draw the armature 101 toward the core 100 against the tension of the spring 103. When the armature is moved toward the core, the end 109 of the armature will urge the pin 85 downwardly to move the ball 83 from the seat 82 against the effect of spring 90 against the valve seat 82a and thus the manifold of the engine communicates with the suction chamber 96 of the device 65 in the following manner: conduit 74a, passages 94, 80, 95 and conduit 74. When this occurs the diaphragm 62 will be drawn to the right as viewed in Fig. 1, exerting a pull upon the rod 61 to rotate the timer 24 in a clockwise direction, to advance the time of sparking impulse.

When the engine is idling or when the engine is not operating the generator sufficiently fast to build up enough voltage to operate the electromagnet 99 the armature will be returned to its normal position, as shown in Fig. 1, by the spring 103 and the spring 90 will urge the pin 91 upwardly to move the ball valve 83 against the upper valve seat 82 to close the passage 94 and connect the chamber 96 with air through the opening 88a. When this occurs the diaphragm will be moved to the left, as viewed in the Fig. 1, by the spring 72. As the diaphragm is moved to the left the rod 61 is also moved to the left to rotate the lever 60 and the ignition timer 25 in a counterclockwise direction, thereby retarding the time of sparking impulse.

While in the drawing, the electromagnetic means 99 is disclosed as having a voltage coil, it is to be understood that the coil may be wound with heavy wire, or series wound, and connected in series with the generator charging circuit so that when the relay 36 closes, the heavy winding will be energized to attract the armature 101 to operate the valve. In this case, all or part of the charging current is used to cause the valve to function.

While the embodiment of the present invention as herein disclosed, constitutes a preferred form, it is to be understood that other forms might be adopted, all coming within the scope of the claims which follow.

What is claimed is as follows:

1. An electromagnetic valve comprising, in combination a flat base, a magnet core perpendicular to the base, a magnet coil surrounding the core, a magnet armature hingedly supported at one side of the coil and extending over the core

to the opposite side of the coil, a valve structure attached to the base on said opposite side of the coil and having a valve operating rod extending parallel to the magnet core and adjacent the free end of said armature, a leaf spring attached to the armature, a bendable abutment member against which the spring bears to bias the spring, to urge the armature away from the core, said abutment member being attached between the coil and the head of the core, and a stop member to limit movement of the armature away from the core, the bending of the abutment member varying the amount of magnetic flux necessary to attract the armature to move the valve member.

2. An electromagnetic valve comprising, in combination a flat base, a magnet core perpendicular to the base, a magnet coil surrounding the core, a magnet armature hingedly supported at one side of the coil and extending over the core to the opposite side of the coil, a valve structure attached to the base on said opposite side of the coil and having a valve operating rod extending parallel to the magnet core and adjacent the free end of said armature, a leaf spring attached to the armature, an abutment member against which the spring bears to bias the spring to urge the armature away from the core, and a bendable stop member to limit movement of the armature away from the core, said stop member being attached between the coil and head of the core, the bending of said stop member varying the air gap between the armature and core thereby varying the amount of magnetic flux necessary to attract the armature to move the valve member.

3. An electromagnetic valve comprising, in combination a flat base, a magnet core perpendicular to the base, a magnet coil surrounding the core, a magnet armature hingedly supported at one side of the coil and extending over the core to the opposite side of the coil, a valve structure attached to the base on said opposite side of the coil and having a valve operating rod extending parallel to the magnet core and adjacent the free end of said armature, a leaf spring attached to the armature, a bendable abutment member against which the spring bears to bias the spring to urge the armature away from the core, a bendable stop member to limit movement of the armature away from the core, and a plate having integral therewith said plate being attached between the coil and head of the core, the bending of said members varying the amount of magnetic flux necessary to attract the armature to move the valve member.

JAMES L. ARTHUR.
